UNITED STATES PATENT OFFICE.

FRANK GRISIUS, OF MILWAUKEE, WISCONSIN.

SHADE-FIXTURE.

1,330,465.

Specification of Letters Patent. Patented Feb. 10, 1920.

Application filed August 23, 1919. Serial No. 319,355.

To all whom it may concern:

Be it known that I, FRANK GRISIUS, a citizen of the United States, and resident of Milwaukee, in the county of Milwaukee and State of Wisconsin, have invented certain new and useful Improvements in Shade-Fixtures; and I do hereby declare that the following is a full, clear, and exact description thereof.

10 My invention pertains to new and useful improvements in shade fixtures, particularly those adapted to control the movements of a shade roller for maintaining the shade in various positions.

15 The primary object of this invention is to provide an arrangement by which the roller of a window shade may be made to revolve in a direction to roll the shade up on the same when a cord is pulled, and the 20 revolutions of said roller may be stopped at any point at any time by simply carrying the end of the cord toward or away from the adjacent edge of the shade and out of a vertical line extending from the pulley 25 element of the arrangement. In this connection provision is made for permitting the shade to readily unroll from the roller to any desired length and then to be surely stopped and held.

30 A further object of the invention relates to the provision of an interchangeable pulley which may be used on either end of a shade roller, and with either a right or left hand bracket.

35 An additional object of the invention is to construct certain other elements of the device from sheet metal whereby the cost of manufacture will be materially decreased.

With these objects in view the invention 40 resides in the novel features of construction, combination and arrangement of parts which will be hereinafter very particularly described and claimed and shown in the drawing, wherein:

45 Figure 1 represents an elevational view of one end of a shade roller and shade having my invention applied thereto;

Fig. 2 is a similar view showing the arrangement of one of my improved devices 50 at the opposite end of a shade roller;

Fig. 3 is a vertical sectional view taken on the plane of the line 3—3 of Fig. 1;

Fig. 4 is an end view of the pulley shown in elevation in Figs. 1 and 2; and

Fig. 5 is a detail longitudinal sectional view through one end of the shade roller.

In certain situations it may be impossible to apply the attachment to the left hand end of a shade roller, while at other times it may be equally impossible to use the invention on the opposite end of a roller. Therefore, the most important, and likewise the most expensive element in this invention is adapted for use at either end of a roller in connection with coöperating elements which may be less expensively manufactured. Reference is made to the pulley 1, it having a central annular groove 2, thus forming annular flanges 3 and 4. A trunnion 5 extends centrally from each opposite side of the pulley, and each of these trunnions is alike so as to make the pulley interchangeable. In other words, the portion of each trunnion adjacent its connection with the pulley is cylindrical, as shown at 5^a, while the free end portions are polygonal in cross section, preferably rectangular, as shown at 5^b in Fig. 4.

The brackets 6 that are used in connection with the pulleys 1 are preferably similarly constructed, except that one is used for the left hand end of a shade roller 7, whereas the other is adapted for use at the right hand end of the latter. In either case the bracket is formed from a substantially rightangular blank of relatively light gage sheet metal having one end portion bent laterally as at 8 to provide an attaching foot, the other end portion being bent laterally in an opposite direction to provide a brake or locking finger 9. As shown in the drawing, the attaching portions 8 are preferably vertically disposed, and the locking fingers are positioned horizontally. The intermediate portion of the blanks which form the brackets are provided with bearing openings for the reception of the cylindrical portions 5^a of the trunnions 5.

A pulley 1 is non-rotatively fixed to either end of the shade roller 7 by means of the rectangular ends 5^b of the trunnions, and an attaching plate 10. From Fig. 5 it will be seen that the plate 10 is also formed of sheet material, the central socket 11 therein,

which receives one of the portions 5^b of the trunnions, is provided by drawing the material of the plate laterally, as is customary in operations of this character. The socket 5 11 being of substantially the same size and shape as the portions 5^b of the trunnions, the pulley will be removably connected with the shade roller 7 when the parts coöperate, as indicated in Figs. 1 and 2.

- 10 An endless cord 12 is disposed around the pulley and normally rests in the annular groove therein. When, however, it is desired to lock the shade roller in any one of numerous positions, this cord 12 is moved 15 laterally out of a vertical line extending from the groove 2 and into any one of several diagonal grooves 13 which are cut in the flange 3. By moving the cord in this manner, rotation of the shade roller will 20 cause said cord to be gripped between the bottom of the groove 13 in which it rests and the locking finger 9.

The operation of the invention is substantially as follows: to lower the curtain, the 25 operator will grasp the lower portion of the cord 12 and permit the lower end of the shade to descend by gravity as it unrolls from the roller 7, letting the cord gradually slip through his fingers until the curtain or 30 shade C has been lowered to the point desired, whereupon he will carry the lower portion of the cord toward or away from the edge of the shade, which will cause the former to ride into either of the diagonal 35 grooves 13. Then upon rotation of the pulley slightly in a proper direction, the cord will be clamped beneath said locking finger 9, as above explained. In raising the shade, the endless cord 12, after being released 40 from beneath the locking finger 9, is pulled in a direction which will cause a rotation of the roller 7 to wind up the shade, and after the bottom of the same has attained a proper height, the cord is again shifted to dispose 45 it in one of the diagonal grooves 13 for subsequent clamping beneath the locking finger 9.

The operations of raising and lowering the shade are practically identical, regardless 50 of whether the pulley 1 is connected with the right hand end or the left hand end of the shade roller. In other words, in both cases the endless cord 12 is moved laterally into one of the grooves 13 when it is desired 55 to retain the roller in one of its several adjusted positions. The fact that the pulley is capable of use at either end of a shade roller, obviously greatly lessens the cost of the device and reduces the number of

parts which it would otherwise be necessary 60 to keep on hand.

Various minor changes may be made in the form and proportions of the several parts of the device to accommodate them for use on rollers of different types, or for 65 other purposes, these changes being within the scope of the invention, as outlined in the appended claims.

I claim:

1. The combination with a roller, of a 70 bracket, a pulley having oppositely extending trunnions, one being journaled in said bracket, the other being detachably fixed to one end of the roller, and a flexible operating member disposed around the pulley. 75

2. The combination with a roller, having a polygonal socket in one end, a bracket having a bearing opening, a pulley having oppositely extending trunnions, one being journaled in said bearing opening, the other 80 being polygonal and removably seated against rotation in said socket, and a flexible operating member disposed around the pulley.

3. The combination with a roller, having 85 a polygonal socket in one end, a bracket having a bearing opening, a pulley having oppositely extending trunnions, said trunnions being alike, the portion of each adjacent the pulley being cylindrical for rotatory engagement in the bearing opening, the free 90 end portion of one being polygonal for non-rotatory engagement in the roller socket, and a flexible operating member disposed around the pulley. 95

4. The combination with a roller, of a bracket comprising a substantially right-angled blank of sheet material having one end bent laterally to form an attaching portion, the other end being bent laterally in an 100 opposite direction to provide a locking finger, the intermediate portion of the blank having a bearing opening, a flange pulley fixed to one end of the roller and journaled in the bearing opening, one flange of the 105 pulley having a diagonal groove communicating with the annular groove therein, and a flexible operating member normally disposed in said annular groove and movable into said diagonal groove to be clamped between the bottom thereof and said locking finger. 110

In testimony that I claim the foregoing I have hereunto set my hand at Milwaukee, in the county of Milwaukee and State of 115 Wisconsin.

FRANK GRISIUS.
